UNITED STATES PATENT OFFICE

93,437

DESIGN FOR A BOTTLE CASING

George E. Ball, New York, N. Y., assignor to The
American Thermos Bottle Company, Norwich,
Conn., a corporation of Ohio

Application June 12, 1934, Serial No. 52,145

Term of patent 14 years

To all whom it may concern:

Be it known that I, GEORGE E. BALL, a citizen of the United States, residing in the city of New York, county and State of New York, have invented a new, original, and ornamental Design for a Bottle Casing, of which the following is a specification, reference being had to the accompanying drawing, forming part thereof.

The figure is an elevation of a bottle casing showing my new design.

I claim:

The ornamental design for a bottle casing, as shown.

GEORGE E. BALL.
